United States Patent Office

Des. 207,529
Patented May 2, 1967

207,529

BACKING PLATE

John R. Morgan, Wheeling, Ill., assignor to Amerock
Corporation, Rockford, Ill., a corporation of Illinois

Filed July 15, 1966, Ser. No. 3,096

Term of patent 14 years

(Cl. D10—8)

FIG. 2 is a top view of the backing plate.

FIG. 3 is an enlarged sectional view taken along the line 3—3 in FIG. 1.

FIG. 4 is an enlarged sectional view taken along the line 4—4 in FIG. 1.

I claim:

The ornamental design for a backing plate, substantially as shown.
